BLAST FURNACE CINDER OR OPEN HEARTH
SLAG POT

Clarence W. Howat, Pittsburgh, Pa.

Application February 19, 1937, Serial No. 126,605

4 Claims. (Cl. 266—39)

My invention relates broadly to pots and it has particular relation to a cinder pot for blast furnaces or to a slag pot for open hearth furnaces.

One of the objects of the invention is to provide a construction of a cinder pot for blast furnaces or a slag pot for open hearth furnaces in which the outside wall area is materially increased, thereby increasing the heat dissipating area of the pot.

10 Another object of my invention is to provide a construction of a cinder or slag pot which substantially prevents side wall deformation present in the pots heretofore employed.

Another object of my invention is to provide a 15 construction of a yoke or bail, employed in conjunction with the cinder or slag pot, which materially assists in reducing the time required for cooling the contents of the pot.

Still another object of my invention is to provide 20 a construction of an improved means for locking the pot to the body of the trunnion ring or bail.

In the construction of a blast furnace cinder pot or a slag pot for open hearth furnaces in 25 accordance with my invention, a pot having plain cylindrical section and a bowl-shaped end section is provided with outwardly extending ribs or fins about the outer periphery thereof. These fins or ribs extend vertically substantially the 30 height of the pot. In addition to the benefits provided for by the aforementioned ribs, a plurality of stools or reinforcing members are formed integral with the side walls of the pot, adjacent the longitudinal center of the walls. Disposed 35 between the reinforcing members and about the outer periphery of the pot is a trunnion ring or bail. The pot is locked to the body of the trunnion ring by means of latches pivotally mounted on some of the reinforcing members of the pot.

40 For a better understanding of the invention, reference may now be had to the accompanying drawings forming a part of the specification in which:

Fig. 1 is a side elevational view of a pot and trunnion constructed in accordance with my invention, with portions broken away for the sake of clearness.

Fig. 2 is a plan view of the pot as shown in Fig. 1.

50 Fig. 3 is a vertical section of a pot, constructed in accordance with my invention, taken substantially along line III—III of Fig. 2, and,

Fig. 4 is an enlarged detail view disclosing the thickness of the ribs with regard to the thickness 55 of the wall of the pot.

In practicing my invention a pot 10, having a wall 11, terminating in a bowl-shaped end 12, is employed. A plurality of radially extending fins or ribs 13 are provided about the outer periphery of the wall, the ribs extending substantially from 5 the top to the bottom of the pot. As shown in Fig. 4, the ribs 13 are of a thickness equal to approximately 30% the thickness of the wall. Moreover, the ribs are equally spaced and they are of sufficient number as to increase the heat 10 dissipating area of the pot approximately 50%.

A plurality of reinforcing members 14 are provided about the outer periphery of the pot. Each of the members 14 are provided with a flange 15, extending outwardly at right angles, with respect 15 to the top of the pot and terminating in a downwardly extending lug 16. The lower surface of the flange 15, as indicated at 17, engages a trunnion 18 having a body portion 19. The body portion 19 is formed with flanges 20 and 21, and 20 is positioned about the outer periphery of the pot with the flange 20 engaging the surface 17 of the reinforcing members 14. To materially increase dissipation of the heat from the pot a plurality of openings 22 are formed in the body 25 of the trunnion 18. The provision, of the openings 22, is important in that the openings permit a rapid dissipation of the heat from the pot adjacent the trunnion ring. A pair of journals 23 formed integral with the body of the trunnion 30 ring and extending outwardly therefrom is provided for supporting the pot and trunnion ring on a furnace car (not shown).

Formed integral with the wall of the pot and positioned below the trunnion 18 is a series of 35 elements 24. The members 24 extend outwardly from the wall as shown in Fig. 3 and they are grouped in pairs, as are the members 14. Arms or latches 25, each having an elongated slot 26 are pivotally mounted, by means of pins, between 40 pairs of the reinforcing members 24, as indicated at 27. Adjacent the outer end of the latch 25 is formed a flange 28, extending upwardly when the latch is in operative position. The latch engages the flange 21 of the trunnion ring and is disposed between a pair of fingers 29, extending 45 downwardly from the body of the trunnion ring. In positioning the pot and locking it to the trunnion ring, each of the latches 25 is placed between a pair of the fingers 29 and locked in position by 50 means of a pin 30 extending through the fingers and coacting with the elongated slot 26 in the latch 25.

From the foregoing description, it will be apparent that I have provided and improved con- 55

struction of a blast furnace cinder pot and slag pot for open hearth furnaces together with a trunnion, which will materially reduce the time required in cooling the contents of the pot, and that the reinforcing members materially assist in providing a pot that is substantially free from side wall deformation.

It is to be understood that the form of the invention herewith shown and described is merely 10 illustrative of a preferred embodiment and that such changes as fall within the purview of one skilled in the art, may be made without departing from the spirit of the invention and the scope of the appended claims.

15 I claim:

1. In a cinder pot for blast furnaces or slag pot for open hearth furnaces comprising a substantially frusto-conical wall portion, a plurality of outwardly extending ribs about the outer periphery of the wall, a plurality of members positioned in rows about the outer periphery of the pot, a plurality of arms pivotally mounted on the lower members, a yoke positioned between the upper and lower rows of members and means engaging the arms for locking the pot to the yoke.

2. A cinder pot for blast furnaces or a slag pot for open hearth furnaces comprising frusto-conical wall portion, a plurality of outwardly extending ribs about the outer periphery of the wall, a plurality of reinforcing members extending outwardly from the wall, each of the reinforcing members having a flange terminating in a downwardly extending lug, a yoke positioned about the outer periphery of the pot, with the

top thereof engaging the reinforcing members, a plurality of members below the yoke and extending outwardly from the wall a plurality of arms pivotally mounted on the lower members and means engaging the arms for locking the 5 pot to the yoke.

3. A cinder pot for blast furnaces or a slag pot for open hearth furnaces comprising frusto-conical wall portion, a plurality of outwardly extending ribs about the outer periphery of the 10 wall, a plurality of members extending outwardly from the wall, a trunnion ring positioned about the outer periphery of the pot, with the top of the trunnion engaging the reinforcing members, a plurality of fingers projecting downwardly from the trunnion ring, a plurality of members below the trunnion and means mounted on the last mentioned members coacting with the fingers for locking the pot to the trunnion ring.

4. A cinder pot for blast furnaces or slag pot 20 for open hearth furnaces comprising a frusto-conical wall portion, a plurality of relatively thin, outwardly extending heat dissipating ribs, the ribs extending vertically from the top to substantially the bottom of the pot, a plurality of members extending outwardly from the wall, a trunnion ring positioned about the outer periphery of the pot, with the top of the trunnion ring 25 engaging the members, a plurality of members positioned below the trunnion ring and means 30 engaging the last mentioned members for locking the pot to the trunnion ring.

CLARENCE W. HOWAT.
